UNITED STATES PATENT OFFICE.

GEORGE A. ENSIGN, OF DEFIANCE, OHIO, ASSIGNOR TO THE DEFIANCE MACHINE WORKS, OF DEFIANCE, OHIO, A CORPORATION OF OHIO.

SPEED-CHANGING MECHANISM.

SPECIFICATION forming part of Letters Patent No. 685,587, dated October 29, 1901.

Original application filed April 9, 1901, Serial No. 55,022. Divided and this application filed July 30, 1901. Serial No. 70,271. (No model.)

To all whom it may concern:

Be it known that I, GEORGE A. ENSIGN, a citizen of the United States, and a resident of Defiance, in the county of Defiance and State of Ohio, have invented a new and Improved Speed-Changing Mechanism, of which the following is a full, clear, and exact description, this being a division of the application for Letters Patent of the United States for an axle-shaping machine, Serial No. 55,022, filed by me April 9, 1901.

The object of the invention is to provide a new and improved speed-changing mechanism which is simple and durable in construction, very effective in operation, and arranged to automatically change the speed of a carriage or other movable part of the machine while traveling in one direction and to stop the carriage or movable part whenever it reaches the end of its stroke.

The invention consists of novel features and parts and combinations of the same, as will be fully described hereinafter and then pointed out in the claims.

25 A practical embodiment of the invention is represented in the accompanying drawings, forming a part of this specification, in which similar characters of reference indicate corresponding parts in all the views.

30 Figure 1 is a plan view of the improvement as applied to an axle-shaping machine such as shown in the application above referred to. Fig. 2 is a transverse section of the same on the line 2 2 in Fig. 1. Fig. 3 is an enlarged 35 transverse section of the improvement, and Fig. 4 is a similar view of the same with parts in a different position.

The speed-changing mechanism may be applied to various machines. As represented 40 in the drawings, it is shown applied to an axle-shaping machine having a bed A, on which is mounted to reciprocate a carriage G, automatically fed forward by a suitable feed mechanism, of which the feed-screw H is shown, 45 the carriage being quickly returned by hand. The carriage supports a revoluble carrier F for a cutter-bar E, provided at its free end with a cutter D for cutting and shaping the rough end of a wooden axle. The feed mech-

anism for the carrier F and the carriage G is 50 driven from the main shaft K, (see Figs. 1 and 2,) journaled in suitable bearings carried on a bracket A⁴, attached to the rear of the bed A, and on said shaft K are mounted to turn loosely pulleys K' K², of which the 55 pulley K' is connected by a belt K³ with a large pulley on a counter-shaft, (not shown,) and the other pulley K² is connected by a belt K⁴ with a small pulley on said counter-shaft, so that when the latter is rotated the pulley K' 60 is rotated at a higher rate of speed than the pulley K². The pulleys K' K² are adapted to be engaged by friction-clutches K⁵ K⁶, connected with each other and mounted to slide on and to turn with the shaft K, a shifting lever K⁷ engaging the hub K⁸, common to said clutches K⁵ K⁶, to move either of the latter into frictional engagement with the corresponding pulley K' or K², and thereby rotate the shaft K at a high rate of speed during the 70 time the cutter D cuts one portion of the axle C or to rotate the shaft K at a low rate of speed during the time the cutter D cuts another portion of the axle. When the lever K⁷ is in a central position, as shown in Fig. 2, 75 then both clutches K⁵ K⁶ are out of frictional engagement with their pulleys K' K², and the shaft K is now at a standstill.

On the shaft K is secured a bevel gear-wheel L, in mesh with a bevel gear-wheel L', secured on the lower end of a vertically-disposed shaft L², journaled in suitable bearings carried by the bracket A⁴. On the upper end of the shaft L² is secured a bevel-pinion L³, in mesh with a bevel gear-wheel L⁴, fastened 85 on the forward end of a shaft L⁵, extending longitudinally and mounted to turn in suitable bearings carried by the bed A. This shaft L⁵ is geared to the carrier F and to the feed-screw H by gearing (not shown) to rotate the carrier and the feed-screw for the latter to automatically feed the carriage G forward.

In order to actuate the shifting lever K⁷ for starting the machine by the operator and in 90 order to automatically shift the double clutch K⁵ K⁶ from the carriage G to run the machine at a low rate of speed at the time the cutter

D has finished one portion of the axle and has started on the other portion, the following arrangement is made: The shifting lever K⁷ is pivotally connected with the rear end 5 of a rod R, extending transversely through suitable openings in the bed A to connect at the forward end with a block R', mounted to slide transversely in suitable guideways formed in a bracket A⁶, secured to the front 10 of the bed A. This block R' is pivotally connected with a treadle R², fulcrumed on the bracket A⁶ and adapted to be pressed by the operator to slide the block R' into a forward position against the tension of a spring R³, 15 secured at its forward end on a rod R⁴, adjustably held in the block R'. The rear end of the spring R³ is secured to a second block R⁵, likewise mounted to slide in the guideway of the bracket A⁶ in the rear of the block R', 20 and this block R⁵ is provided with a longitudinal pin R⁶, extending through elongated slots in the sides of the guideway of the bracket A⁶, as is plainly shown in Fig. 2, and the outer ends of said pin R⁶ are adapted to 25 be engaged by arms S, secured on a shaft S', mounted to turn in suitable bearings carried on the guideway of the bracket A⁶. A treadle S² is secured on this shaft S' and is under the control of the operator, and said treadle is 30 formed with an extension S³, adapted to rest on a rubber block S⁴, carried by the bracket A⁶ and serving to limit the upward-swinging motion of the treadle S². The tops of the blocks R' R⁵ are formed with shoulders R⁷ R⁸, 35 respectively adapted to be engaged by dogs T T', loosely fulcrumed on the shaft S', so that when the operator presses the treadles R² and S³ and causes the blocks R' and R⁵ to slide in opposite directions then the dogs T 40 T' drop and by their free ends engage the shoulders R⁷ R⁸ to lock the blocks R' R⁵ in position against the tension of the spring R³, as is plainly indicated in Fig. 3. The dogs T T' are pivotally connected by upwardly-extending links T² T³ with arms T⁴ T⁵, secured on longitudinally-extending shafts U U', mounted to turn in suitable bearings carried by brackets A⁷, attached to the bed A. On the shafts U U' are adjustably held upwardly-extending arms U² U³, carrying at 45 their upper ends friction-rollers U⁴ U⁵, adapted to be engaged by a pin U⁶, depending from a bracket U⁷, secured to the front of the carriage G. Now when the carriage G moves 50 forward the depending pin U⁶ first comes in contact with the friction-roller U⁴ and imparts an outward-swinging motion to the arm U² to rock the shaft U, and thereby give an upward-swinging motion to the arm T⁴ to 55 cause the link T² to swing the dog T upward out of engagement with the shoulder R⁷, and thereby release the block R', which is now pulled inward by the action of the spring R³. The inward movement of the block R' causes 60 the rod R to impart a swinging motion to the shifting lever K⁷ to move the double clutch out of engagement with the pulley K' and

into engagement with the pulley K² to rotate the shaft K at a low rate of speed. The arm U² is so adjusted on the shaft U that the 7c above-described movement takes place at the time that the cutter D has finished one end of the axle and starts on the other portion of the axle. When the oblong portion of the axle has been finished by the cutter D, then 75 the depending pin U⁶ moves in engagement with the friction-roller U⁵ to swing the arm U² transversely, and thereby rock the shaft U', so that the arm T⁵ is swung upward, and its link T³ imparts an upward-swinging motion to the dog T' to release the block R⁵, so 80 that the block R' is relieved from the tension of the spring R³, and the said blocks R' R⁵, the rod R, the lever K⁷, and the friction-clutches K⁵ K⁶ move to a central position, and the clutches K⁵ K⁶ are now out of frictional engagement with the pulleys K' K², so that the shaft K comes to a standstill, and with it the working parts of the machine. The link T² is provided with a weight T⁶ for holding the 90 dog T securely in a locked position against the shoulder R⁷ of the block R'. The ends of the shafts U U' are provided with handles U⁸ U⁹, adapted to be taken hold of by the operator to enable the latter to turn said shafts 95 whenever desired to actuate the shifting lever K⁷ and throw the clutches K⁵ K⁶ in or out of mesh with the pulleys K' K².

The operation is as follows: When the carriage G has been moved into a lowermost 100 starting position, then the operator presses the treadles R² S³ to slide the blocks R' R⁵ in opposite directions and lock the same in place by the dogs T T'. The outer end of the block R' causes a pull on the rod R, so that the lever K⁷ is swung to throw the clutch K⁵ in engagement with the high-speed pulley K', so 105 that the shaft K is now rotated, and with it the shaft L', which in turn drives the screw-shaft H and the carrier F. When the cutter D reaches the end of the first part of the axle, then the arm U⁷ acts on the friction-roller U⁴ to shift the clutch device, so that the speed of the shafts K⁷ and L⁵ and that of the feed-screw H and the carriage G is reduced, as 110 above explained. The second portion of the axle is now formed under reduced speed on the turning and forward movement of the cutter D. When this portion of the axle is 115 finished, the arm U⁷ engages the friction-roller U⁵ to release the block R⁵ and cause the friction-clutch to assume its former or central position. The shaft K now comes to a standstill.

Having thus fully described my invention, 125 I claim as new and desire to secure by Letters Patent—

1. A speed-changing mechanism, comprising a shaft, pulleys loose on said shaft and driven at different speeds, a double friction-clutch mounted to slide on and to turn with said shaft and adapted to be thrown in mesh with either of said pulleys, a shifting lever 130 for said double clutch, a sliding block con-

nected with said shifting lever, a second sliding block having a spring connection with said first-named sliding block, means for moving said blocks in opposite directions, locking-dogs for engaging and locking the blocks in an outermost position, and means for successively throwing the dogs out of engagement with said blocks, as set forth.

2. A speed-changing mechanism, comprising a shaft, pulleys loose on said shaft and driven at different speeds, a double friction-clutch mounted to slide on and to turn with said shaft and adapted to be thrown in mesh with either of said pulleys, a shifting lever for said double clutch, a sliding block connected with said shifting lever, a second sliding block having a spring connection with said first-named sliding block, means for moving said blocks in opposite directions, locking-dogs for engaging and locking the blocks in an outermost position, and means for successively throwing the dogs out of engagement with said blocks, the last-mentioned means comprising rock-arms adapted to be successively rocked from a moving part of the machine, and links connecting said rock-arms to said dogs, as set forth.

3. A speed-changing mechanism having a setting device for a double clutch, comprising a pair of sliding blocks, one of which is connected with the shifting lever of the

clutch, means for moving the blocks apart, and dogs for engaging the blocks when moved apart, to hold the same locked in this position, as set forth.

4. A speed-changing mechanism having a setting device for a double clutch, comprising a pair of sliding blocks, one of which is connected with the shifting lever of the clutch, means for moving the blocks apart, dogs for engaging the blocks when moved apart, to hold the same locked in this position, and means for successively throwing said dogs out of engagement with the blocks, as set forth.

5. A speed-changing machine having a setting device for a double clutch, comprising a pair of sliding blocks, one of which is connected with the shifting lever of the clutch, treadles for moving the blocks apart, dogs for engaging the blocks when moved apart to hold the same locked in this position, means for successively throwing the dogs out of engagement with said blocks, and a spring connecting the blocks with each other, as set forth.

In testimony whereof I have signed my name to this specification in the presence of two subscribing witnesses.
